UNITED STATES PATENT OFFICE.

WILLIAM WILSON HAMILL, OF GLASGOW, SCOTLAND.

CARBURETER.

1,104,494.

Specification of Letters Patent. Patented July 31, 1914.

Application filed September 7, 1911. Serial No. 648,190.

To all whom it may concern:

Be it known that I, WILLIAM WILSON HAMILL, a subject of the King of Great Britain, residing at Glasgow, Scotland, have 5 invented certain new and useful Improvements in Carbureters for Internal-Combustion Engines, of which the following is a specification.

This invention relates to carbureters for 10 internal combustion engines and its object is to improve the construction of such apparatus while rendering same more efficient than hitherto and improving the regulation and controllability of the engines to which 15 they are fitted.

Heretofore, in internal combustion engines, various arrangements have been proposed for regulating the volumes of fuel and air according to the demand of the engine but such arrangements have been generally operated by hand or by mechanical means actuated from some suitable moving part of the engine and are not sufficiently sensitive. Irregularity in the fuel supply 25 has also been found to take place due to variations in the velocity of the air in the vicinity of the fuel sprayer or jet orifice.

Under my invention I provide a valve device for automatically controlling the proportion of fuel to air, this device being very sensitive in operation. It is acted upon by gravity and its movements are automatically effected and controlled by the volume of the charge passing to the engine, no 30 spring-controlled valves or other mechanical arrangements being necessary. This valve device is so constructed that the velocity of the air in the vicinity of the sprayer or jet orifice is kept practically constant under all 35 working conditions. The arrangement is also such that all the air required for combustion and supplied to the mixing chamber must pass through the said chamber and be regulated by the device.

40 The invention also comprises certain improvements in the jet sprayer apparatus whereby the area of the annular orifice can be regulated with great exactitude, and in the means for regulating the supply of air to the carbureter, and also to improvements in the float valve mechanism the chamber of which is provided with means for filtering the hydrocarbon before it passes to the sprayer.

45 In order that the invention may be clearly

understood I have hereunto appended explanatory drawings which show by way of illustration or example two modes of constructing the carbureter.

On the drawings:—Figure 1 is a vertical section of one form of carbureter. Fig. 2 is a part side view and part section on the line 2, 2, Fig. 1. Fig. 3 is a vertical section of a slightly modified form of carbureter. Fig. 4 is a sectional elevation of the jet sprayer apparatus for spraying the fuel.

Referring to Figs. 1 and 2 of the drawings the carbureter comprises a casing 1 having in the lower portion thereof a series of openings 3 for the passage of air thereto. A detachable air inlet sleeve 4 is fitted around the openings 3, being mounted in suitable annular recesses 5 in the casing 1, and this sleeve 4 is made in two parts adapted to be placed in the said recesses 5 and to be secured together by means of screws 6 and snugs or projections 7.

The sleeve 4 is made with an air inlet opening 8 and a flange 9 by means of which a hot air supply pipe may be secured thereto, and the arrangement is such that the sleeve can be rotated in a horizontal plane in order to bring the flange 9 into a convenient position for connection with the air supply pipe. The bottom 10 of the casing 1 has a series of pairs of diametrically opposite screw holes 11 any of which pairs is adapted to receive a pair of screws 12, which screws are each passed through a curved slot or opening in a cover or base 13 in such manner that the cover or base 13 is secured to the casing 1 by means of the screws 12 and may, on the screws being sufficiently loosened, be rotated in a horizontal plane, the screws during this rotary movement traversing the slots in the cover or base 13. The cover or base 13 is provided with a passageway 45 therein for the admission of fuel to the sprayer.

Extending upward through the cover or base 13 and through the bottom 10 of the casing 1 is a suitable jet sprayer apparatus 14, which apparatus, as shown clearly at Fig. 4, consists of a spray nozzle 56, preferably of a tubular formation, and provided at its upper end, with a circumferential and upwardly projecting knife edge 57 concentric with and communicating at its interior with the axial fluid passage 58 of the nozzle 56. Near the lower end of the nozzle 56

100

105

110

is a conical part 59 adapted to seat rotatably in a corresponding recess in the casing 1 (see Figs. 1 and 3) of the vaporizer or carbureter, said conical part 59 having a circumferential groove 60 communicating with the fluid inlet passage 45 of the vaporizer or carbureter and, by way of a radial passage or passages 62, communicating with the axial passage 58 of the nozzle 56.

- 10 A collar 63 which fits over a reduced or grooved part 64 on the lower end of the nozzle 56 is provided with a set screw 65 which latter secures the collar to the reduced or grooved part 64 of the nozzle. Surmounting said knife edge 57 is an adjustable head 66 provided with a corresponding annular but downwardly projecting knife edge 67, said knife edge being, preferably, formed by making the underside of the head with 20 an annular cavity 68 against which the fluid is adapted to impinge before passing out between the knife edges, thereby absorbing the momentum of the fluid. The aforesaid head 66 is carried at the end of a spindle 69 25 passed through the axial passage 58 of the nozzle, said spindle being provided with one or more projections 70 adapted to fit said axial passage and thereby maintain the upper knife edge 67 concentric with and 30 in proper relation to the lower knife edge 57. The lower end of the aforesaid spindle 69 is provided with a very fine screw thread 71 engaging a similarly threaded part 72 in the axial passage of the nozzle and the 35 lower end of said spindle 69 is also provided with a squared part 73 on which is fixed a micrometer wheel 74 by means of a correspondingly shaped squared recess 79.
- The end of the spindle 69 is provided with 40 a screw thread 75 with which engages a nut 76, the said nut holding the micrometer wheel 74 in engagement with the square part 73 of the spindle 69. The said micrometer wheel may be formed with a boss 78 adapted 45 to fit in a recess in the extended lower extremity of the nozzle 56 so as to form a packing gland and thereby prevent leakage of any fluid which may have worked through between the threaded part 72 of 50 the axial passage and the screwed part 71 of the spindle. The micrometer wheel is suitably graduated and its upper flange works over the collar 63 which is provided with a zero mark at Z. The zero mark can 55 be set at different positions to compensate for wear or damage by slackening the screw 65 and turning the collar 63 and thereafter again tightening the screw. The micrometer wheel, after adjustment, may be prevented from rotating by tightening the nut 60 76. By means of the micrometer adjustment the area of the circumferential orifice 15 of the nozzle of the sprayer can be regulated with great exactitude.

65 The sprayer apparatus 14 is inserted from

the underside of the cover or base 13 and is held in position by means of a spring arm 16 pivotally mounted on a set pin 17 and having a recess at its outer end adapted to engage a second pin 18 and a second recess adapted to engage a shoulder on the sprayer apparatus and by simply depressing slightly the outer end of the arm 16 and turning the same back on its pivot pin 17 the sprayer is released and may drop, or be withdrawn, 75 from the carbureter.

Mounted concentrically on the jet of the sprayer or its equivalent 14 is a sleeve or its equivalent 19 which may be termed the "fuel sleeve" and this sleeve or its equivalent 19 is provided with two diametrically opposite orifices or openings 20 of somewhat tapered or triangular shape, the upper ends of which orifices or openings 20 are, when the apparatus is out of operation 80 just below the jet orifice 15, and the arrangement is such that when the "fuel sleeve" moves upward on the jet, while the device is in operation the rate of increase in width and, consequently, the area of the 85 annular orifice cleared is proportional to the increased volume of air passed through the carbureter, as will be hereinafter clearly described.

Secured to the upper end of the "fuel sleeve" 19 by means of a transverse pin 21, or otherwise, is a hollow or tubular receptacle or piece 22 which may be termed an "air sleeve". This "air sleeve" is so constructed at its lower end that a concentric 95 air passageway 23 is formed between it and the "fuel sleeve". The lower end is also preferably of tubular formation and has internally a somewhat conical formation at its extremities and the lower extremity is 100 made with one or more openings or gaps (not shown) for the admission of air to the passageway 23 when the "air sleeve" is in its lowermost, or normal, position. Centrally and externally the "air sleeve" takes 105 the form of an inverted cone whose upper end 24 circumferentially closes an inlet to the mixing chamber 25 of the carbureter. The "air sleeve" is also in its upper portion provided with a series of openings 26 110 in its circumference while above the series of openings it forms a hollow stepped cylinder 27 which is adapted to work in a corresponding recess in the casing 1 in such manner that an air space 28 is provided between 115 the stepped cylinder 27 and the recess so that when the "air sleeve" moves upward during the operation of the carbureter an air cushion or dash pot is provided for the purpose of steadyng the action of the 120 sleeves 19, 22, and for damping out the periodic vibrations due to engine and road shock and to the inertia due to the weight of the sleeves.

On the upper end of the casing 1 is pro- 125

vided a throttle valve 29 of hollow cylindrical shape and fitted in the casing 1 transversely thereof. The throttle valve 29 has suitable orifices or ports 30, 31, preferably 5 of rectangular shape which, when the valve is open, communicate with the mixing chamber 25 in the interior of the casing and with the usual connection 32 to engine cylinder, or with an opening 33 in the casing provided with a suitable wire gauze or other air filter device 34 and with the usual connection to engine cylinder. By means of this construction of throttle valve a tight throttle may be obtained providing a 10 vacuum brake to engine, or a proportionate opening of the throttle throughout its complete range or, if desired, an air scavenge and brake at full throttle, the air to scavenge port being drawn through the air filter 34 15 while the port or orifice communicating with the mixing chamber 25 is completely closed. When the throttle valve is completely closed the "air sleeve" and "fuel sleeve" drop 20 downward into the inoperative position 25 thereby closing the air passage to mixing chamber and at the same time completely cutting off the supply of fuel. The throttle valve 29 is provided with a control lever 35 adapted to operate between suitable stop pins or the like which, if desired, may be 30 adjustably secured in an annular dovetailed slot 36 and are fitted in connection with the lever 35 to enable the movement of the valve to be regulated to any desired extent. A 35 suitable float valve device and chamber 37 communicating by means of a pipe 38 with the fuel reservoir and by means of the passageway 45 with the sprayer 14 is also provided for regulating the level of the fuel 40 supply to the sprayer, and fitted circumferentially in the interior of this chamber 37 is a simple annular filtering device which 45 is preferably in the form of a strip of wire gauze 39 or its equivalent which may be secured in place on a perforated ring 40, frame, or such like adapted to make a tight joint on its exterior edges so as to be readily removed without tools for cleaning purposes.

The valve spindle 41 of the float valve 42 50 is so arranged that its connection with the float 43 is capable of being accurately adjusted from time to time as may be required for the purpose of compensating for wear on valve and valve seat and further to 55 adjust the level for fuels of varying density.

The chamber 37 of the float valve device 60 is provided with a suitable cover 44 having suitable fastening means preferably in the form of spring clips so arranged that by a partial rotation the cover, when required, can be readily removed or replaced.

In the carburetor of modified construction shown at Fig. 3 the arrangement is 65 similar to that shown at Figs. 1 and 2 except that the sleeve 4 is dispensed with and

the casing and "air sleeve" are of somewhat different construction. In this carburetor the casing 46 is made with an internal web or partition 47 having an opening through which air is admitted to the mixing 70 chamber 25. The "air sleeve" 48 is secured to the "fuel sleeve," as in the arrangement shown at Figs. 1 and 2, by means of a pin 21, but the stepped cylinder is, in this case, dispensed with, the upper part of 75 the sleeve 48 engaging the opening in the said web or partition 47 for regulating the passage of air. Secured on the lower end of the sleeve 48 is a piston or head 49 adapted to work within a cylindrical projection 80 50 suitably secured on the cover or base 13. A series of openings 51 are provided in the sleeve 48 just above the piston or head 49 for admitting air to the annular air passage 23, and communicating with the space between the piston or head 49 and the cover or base 13 is a small passageway (not shown) by means of which the admission of air to or the exhaust of air from the said space is 85 permitted, the said space thus serving the 90 same purpose as the annular air space 28 or dash pot device described with reference to Figs. 1 and 2. The lower part of the casing 46 is open, having four upright supporting strips, or arms 54 outside of which 95 a strip or sheet of wire gauze 55 is provided around the casing, atmospheric air passing through the wire gauze to the interior of the casing.

Around the mixing chamber 25 there is 100 provided a jacket or annular chamber 52 having pipe connections 53 for either hot water or exhaust gas jacketing.

With carburetors as constructed under this invention the relative admixture of 105 hydrocarbon to air is maintained constant, from "no load" to "full load" volume irrespective of the rapidity of the change, the arrangement being such that should the volume increase or diminish in unit time the 110 air velocity in proximity to the sprayer of the carburetor is still maintained at its normal value but the increased or diminished volume is automatically provided for by an 115 increase or diminution in the available air opening in the mixing chamber and coincidentally a corresponding increase or diminution in the jet orifice of the sprayer by the movement of the fuel and air sleeves thereby regulating the quantity of hydrocarbon 120 sprayed in accordance with the volume of air. As the efflux of hydrocarbon is directly influenced by the air velocity around the sprayer, and as already mentioned, is maintained constant thus obviating disturbances in the flow of hydrocarbon due to variability in air velocity in the vicinity of jet sprayer. As the increase or diminution in 125 volume of air passing, the effective area of the jet of the sprayer is correspondingly 130

increased or diminished thereby maintaining the mixture homogeneous by preserving the ratio of hydrocarbon to air at all times.

Having now fully described my invention 5 what I claim and desire to secure by Letters Patent is:—

1. A carbureter having, in combination, a fuel spraying device, having an outer part with a circular and tapered outlet and an 10 inner part which is adjustable, means for adjusting the inner part, a sleeve concentric with the said device for controlling the air supply, an inner concentric sleeve slidably mounted on the said device for controlling 15 the fuel supply and means whereby the inner sleeve is operated from the outer sleeve.

2. A carbureter having, in combination, a fuel spraying device, having an outer part and an inner part with circular head thereon which is adjustable, means for adjusting 20 the inner part, a sleeve concentric with the said device for controlling the air supply, an inner concentric sleeve slidably mounted on the said device for controlling the fuel 25 supply and means whereby the inner sleeve is operated from the outer sleeve.

3. A carbureter having, in combination, a fuel spraying device, having an outer part with a circular knife edge outlet, and an 30 inner part with head having a depending knife edge thereon and which is adjustable, means for adjusting the inner part, a sleeve concentric with the said device for controlling the air supply, an inner concentric 35 sleeve slidably mounted on the said device for controlling the fuel supply and means whereby the inner sleeve is operated from the outer sleeve.

4. A carbureter having, in combination, a 40 casing with a tapered opening therein, a fuel spraying device, having an outer part which externally is partly cylindrical and partly conical, said conical part engaging the aforesaid tapered opening in the casing 45 and an inner part which is adjustable, means for adjusting the inner part, a sleeve concentric with the said device for controlling the air supply, an inner concentric sleeve slidably mounted on the said device for controlling 50 the fuel supply and means whereby the inner sleeve is operated from the outer sleeve.

5. A carbureter having, in combination, a fuel spraying device pushed into the carbureter, means for removably holding the device in position in the carbureter in such manner that no tool is required to remove the same, a sleeve concentric with the said device for controlling the air supply, an inner concentric sleeve slidably mounted on the said device for controlling the fuel supply and means whereby the inner sleeve is operated from the outer sleeve.

6. A carbureter having, in combination, a fuel spraying device pushed into the carbureter, pivoted spring means for removably holding the device in position and pressing it tightly in place, a sleeve concentric with the said device for controlling the air supply, an inner concentric sleeve slidably mounted on the said device for controlling the fuel supply and means whereby the inner sleeve is operated from the outer sleeve. 65

7. A carbureter having, in combination, a fuel spraying device push jointed in the carbureter, a pivot, a pivoted lever for holding the device in the carbureter and adapted to turn on the said pivot, a sleeve concentric with the said device for controlling the air supply, an inner concentric sleeve slidably mounted on the said device for controlling the fuel supply and means whereby the inner sleeve is operated from the outer sleeve. 70 80

8. A carbureter having, in combination, a fuel spraying device, having an outer casing with an upwardly projecting knife edge at the top thereof, a spindle passing through said casing and having a head with a downwardly projecting knife edge thereon, the space between the knife edges forming an annular orifice, means for adjusting the upper knife edge with respect to the lower knife edge, a sleeve outside of and concentric with the said device for controlling the air supply, an inner concentric sleeve slidably mounted on the said device for controlling the fuel supply and means whereby the inner sleeve is operated from the outer sleeve. 85 90 95

9. A carbureter having, in combination, an outer casing having a tapered opening in the base thereof, a passage in the casing leading from the fuel supply to said tapered opening, a fuel spraying device having an axial fluid passage and an annular orifice and the exterior thereof partly cylindrical and partly conical, the conical part engaging with the tapered opening in the outer casing, a channel extending around the conical part of the fuel spraying device and registering with the aforesaid passage in the outer casing, a passage extending from said channel to the axial fluid passage, a sleeve outside of and concentric with the said device for controlling the air supply, an inner concentric sleeve slidably mounted on the said device for controlling the fuel supply and means whereby the inner sleeve is operated from the outer sleeve. 100 105 110 115

In testimony whereof I affix my signature in presence of two witnesses.
